UNITED STATES PATENT OFFICE.

WALTER WILLIAM COLLEY, OF LONDON, ENGLAND.

REGISTERING TICKET-PUNCH.

SPECIFICATION forming part of Letters Patent No. 506,158, dated October 3, 1893.

Application filed November 10, 1892. Serial No. 451,576. (No model.)

To all whom it may concern:

Be it known that I, WALTER WILLIAM COLLEY, a subject of the Queen of Great Britain, residing at London, England, have invented 5 certain new and useful Improvements in Alarm and Ticket Punches; and I do hereby declare the following to be a full, clear, and exact description of the invention, such as will enable others skilled in the art to which it 10 appertains to make and use the same.

This invention relates to improvements in the construction of bell alarm and registering punches, whereby when desired, the punch can be worked to register only when a ticket 15 is inserted in the opening for it and punched, as until a ticket is inserted and the punch partially operated the working parts are out of gear from the counting and bell alarm apparatus, and come into gear only through the 20 resistance given by the ticket to a part of the mechanism. After a ticket has been punched the working parts are thrown out of gear from the counting and bell alarm apparatus and are brought into gear again only by 25 a fresh ticket being punched.

While the working parts of the punch are out of gear, it is not possible for the counting apparatus to be moved, or the bell to be sounded, except as hereinafter stated. When 30 a ticket is inserted and the lever partially depressed, the ticket is secured in and cannot be moved out of the apparatus until it has been punched and consequently registered and the piece punched out, passed into the 35 chamber arranged to receive it.

A punch according to this invention may be made either single, double, or treble; that is a separate receiving part made for each ticket of different colors to be punched, and 40 the registering part of the punch operating only for that part in which the ticket has been punched.

To enable this invention to be properly understood, I will proceed to describe the same 45 with the aid of the accompanying drawings.

Figure 1 illustrates an elevation of the punch with one side hinged-cover removed and a portion of the frame and apparatus shown in section; in this view the punch is 50 in its inoperative position, that is before a ticket has been inserted, and all the working parts out of gear from the counting and bell

alarm apparatus. Fig. 2 is a view similar to Fig. 1 but with the different parts in action produced by the insertion of a ticket which 55 has been secured by partial depression of the lever and is about to be punched. Fig. 3 is a vertical section on the line 3, 3, of Fig. 1, of the inner end of the operating lever, and other parts in relation thereto. Fig. 4 is a 60 perspective view of the piece J. Fig. 5 is a perspective view of the rod I that supports the punch. Fig. 6 is a detail view of the punch. Fig. 7 is a detail view of the rod I and punch carried thereby in the act of per- 65 forating a ticket. Fig. 8 is a detail view showing a modified form of bar I, in which modified form of construction a stop pin V inserted in the bar is adapted to fasten the latter, and so enable the bell punch register- 70 ing apparatus to be worked without the insertion of a ticket, by the depression of the operating lever. Fig. 9 is a partial side elevation of a treble arrangement of punches.

The part marked A illustrates the frame of 75 the punch in which the different working parts are held; B the opening for the insertion of the ticket to be punched; C guide collar for end of punch; D the die plate, E receptacle for the punched pieces which are 80 pressed through the hole F; G depressible lever pivoted at G' and held normally in the position shown in Fig. 1 by the spring G²; the angle part G³ terminates in a fork G⁴, which operates the punch H. 85

I is a rod having the front portion I' rounded which works through the hollow punch, and the back portion I² flattened with a notch I³ with incline end I⁴ and a higher part I⁵.

The punch H,—Fig. 6—has a forked end 90 H' by which it is attached to the piece J—Figs. 3 and 4—between the standards J' by screws J². Projecting from the punch H, is a pin H² to secure the ticket.

J³ is an upright slotted guide part on J, to 95 enable it to slide on the flattened part I². On one side of the piece J is a stud J⁴ and on under side are two cam pieces J⁵ and J⁶; on the side of the cam J⁵ is a projection J⁷.

K, is a spring attached to top of the up- 100 right slotted guide J³, and to the pivoting pin of the cam N.

K', is a spring on the rod I, one end bearing against the pendent guide bracket M, and

the other against the collar I⁶. This spring K' is of less strength than the spring G², so that the latter one overcomes the former when the punch is out of use.

5 N is a cam pivoted in the frame A and having secured thereto the bell hammer N'; O, a registering numbering apparatus of usual construction, operated by the lever P, and pendant pawl P', the upper part P² of 10 this lever engages the cam J⁶.

Q, is a spring to operate the bell hammer N' and is secured to the cam N, and T, is the ticket to be punched.

15 The punch works as follows:—Assuming the parts to be in their normal position as shown at Fig. 1, if no ticket is placed in the opening B, and the lever G, is depressed, the fork G⁴ moves forward the punch H, carrying the piece J, with it, which piece J continues in the position shown in Fig. 1 being held up by the part J³ resting upon the top I⁵. This holding up of the part J on the rod I, moving forward causes the cams J⁵, J⁶ to escape the cam N and part P² of lever P. Consequently the registering apparatus is not operated or the bell rung. On the lever G, rising to its normal position by the strength of the spring G², the different parts come back to the position shown in Fig. 1.

20 Referring to Fig. 2, a ticket T, is here shown in the opening B, preparatory to being punched and secured from withdrawal by the pin H² passing through it owing to the partial depression of the lever G, which operates the mechanism, as follows: On the lever G, being partially depressed as aforesaid, the fork G⁴, moves forward the punch H, forcing the pin H² through the ticket, and at the same time the spring K' moves forward 25 the rod I, the point I' of which passing through the hollow punch H, bears against the ticket with the strength of the spring K', as shown in Fig. 7, its forward movement being thereby checked. On the lever G, being further depressed the punch H, moves closer to the ticket and at the same time moving forward part J, and owing to the rod I, remaining stationary by bearing against the ticket, the part J³, passes the higher part I⁵ when the 30 spring K, pulls the part J³ down into the notch I³ in the rod I which allows the cam J⁵ to come into a line to engage the cam N to operate the bell hammer and the cam J⁶ to engage the projection P² on the lever P', to 35 operate the registering apparatus, at the same time the stud J⁷ comes down in a line with the stud S, against which it bears or wedges, thereby retaining the lever G, in the forward position shown in Fig. 2, but allowing it to be 40 further depressed. At this position the ticket T, cannot be got out until the lever G, is further depressed which forces the punch through the ticket thereby moving forward the part J, operating the cam N, and lever P, by the cams J⁵, and J⁶. On the punch passing through the ticket the spring K', forces 45 forward the rod I the front portion I' of which

shoots through the hollow punch and through the hole in the ticket, which forward movement causes the incline I⁴ to meet the under 7c side of the top of part J³ and cause it to slide up onto the top of I⁵, thereby lifting up the cams J⁵ and J⁶ free of the cam N, and arm P², and the side stud J⁷ from engaging stud S, in the backward movement, when all the parts come 75 into the position shown at Fig. 1. In this backward movement which is caused by the strength of the spring G², the stud J⁴, engages the arm P³ and so lifts up pawl P', in readiness to engage the ratchet wheel V of the registering apparatus on the punching of the next ticket. The numbers on the registering apparatus are seen through the window U.

80 Referring to Fig. 9, B', is a sliding piece moved forward by depressing the lever G, 85 through the medium of a rack on the end of the former and teeth on the end of the latter. The punches H, are connected to this piece B', by arms C', by which the punches are forced forward to punch the ticket. The 90 rods I are similar in construction and operation to those previously described, while the pieces J are similar to those previously described and are pivoted to the several arms C', the said pieces J having the upright slotted guides J³ thereon. Pendent from each of the pieces J is a pivoted rod L engaging by its forked ends a stud on a bar M', the said bar having its ends journaled in brackets M², on the piece B', so that it may be turned 95 around. On the bar is the lug Y². Pivoted to the piece B' are crank levers W, from one end of which hang pawls X, to operate the registering apparatus, and on top of the other end is a finger bearing Y, to engage a stud Z, on side of slotted guide J³. On a ticket 100 being inserted in one of the openings B, and the lever G, depressed the part B' is moved forward correspondingly moving forward the punch H and allowing the ends of 105 16, to bear against ticket; further movement of the punch causes the piece J⁹, to fall or be drawn into the notch on 16, thereby turning the bar M', and bringing the cam M², into position to engage lug N, and at the same time the 110 stud Z, moves from over finger Y. On full depression of the lever G, to punch the ticket, the pawls X, fall down to engage a tooth of ratchet wheel and on backward movement of piece B', by spring (not shown in drawings) 115 120 the stud Z, engages the finger Y, lifting up the pawl and moving the ratchet wheel one tooth of that registering apparatus belonging to the part in which the ticket was punched, and all the parts come back to the position 125 shown in drawings. There is also provided the stop S secured in the frame, as above described.

If desired a separate chamber for the punched pieces can be provided for each 130 punch, for the purpose of keeping the different colored pieces separate, as these represent tickets of different values.

Having now described my invention, what

I desire to secure by Letters Patent of the United States is—

1. The combination with a punch, of a spring pressed notched rod adjacent thereto, an actuating lever for the said punch, a piece having cams thereon, pivoted at one end to the said lever and supported by the said notched rod, and a registering mechanism actuated by said cams upon the movement of the said piece when dropped by the said rod, substantially as described. 5
2. The combination, with a hollow punch, of a spring pressed rod partially contained therein and having its projecting end notched, a movable part actuating the said punch, a piece pivoted to the said movable part and supported by the said notched rod and a registering mechanism actuated by the movement of the said piece when dropped by the said rod, substantially as described. 15
3. The combination with a punch, of a spring-pressed notched rod adjacent thereon and normally bearing on the said punch, a movable part actuating the said punch, a piece pivoted to the said movable part and supported by the said notched rod, and a registering mechanism actuated by the movement of the said piece when dropped by the said rod, substantially as described. 25
4. The combination with a hollow punch, of a spring-pressed rod partially contained therein and normally bearing against the said punch, the projecting end of the rod being notched an actuating lever for the said punch, a piece provided with a cam, and with an upwardly-projecting slotted guide, the said piece being connected with the said lever and the said guide resting on the said rod, and a tripping mechanism adapted to be engaged by

the said cam when the said piece is dropped by the said rod and is moved by the said lever, substantially as described. 40

5. The combination with a punch, of a spring pressed, notched rod adjacent thereto, a pivoted lever actuating the said punch, a piece provided with a cam and with an upwardly extending slotted guide, the said piece being connected with the said lever and the said guide resting on the said rod, a tripping mechanism adapted to be engaged by the said cam when the said piece is dropped by the said rod and moved by the said lever and a locking stud adapted to engage the said piece against rearward motion when so dropped and moved, substantially as described. 55

6. The combination with a hollow punch, of a securing pin projecting in front thereof, a spring pressed rod partially contained in the punch and normally bearing thereon, the projecting end of the said rod being notched, a pivoted lever actuating the said punch, a piece provided with projections and an upwardly extending slotted guide, the said piece being connected with the said lever and the said guide resting on the projecting portion of the said rod, a tripping mechanism adapted to engage one of the said cams on the dropping of the said piece and the forward movement thereof by the said lever, and a stop engaging the said piece when so dropped and at the end of its forward movement, substantially as described. 65
